CLAIM

The ornamental design for a fashion ornament for a handbag, as shown and described.

DESCRIPTION

FIG. 1 is a front perspective view of a fashion ornament for a handbag showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view of the fashion ornament shown in FIG. 1, shown in the environment of a handbag. The evenly dashed broken lines depict environment and form no part of the claim.

1 Claim, 5 Drawing Sheets
